Primary Examiner—Ruth McInroy(74) *Attorney, Agent, or Firm*—Weide & Miller, Ltd.(57) **CLAIM**

The ornamental design for a combined wet and dry vacuum, as shown and described.

DESCRIPTION

FIG. 1 is a front isometric view of a combined wet and dry vacuum showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The portions of the design shown in dotted line form no portion of the claimed design.
